UNITED STATES PATENT OFFICE

2,480,920

AUTOMATICALLY ADJUSTABLE HAIR CLIPPER

Jacob Gullong, Chicago, Ill., assignor of fifty per cent to Henry Wehming, Chicago, Ill.

Application October 11, 1947, Serial No. 779,394

12 Claims. (Cl. 30—202)

1.

My invention relates to hair-clipping devices. An important object of my invention is to provide a hair-clipping attachment device that may be mounted quickly upon any standard type of hair clipper, merely by making use of the existing assembly screws in the guide plate of the said hair clipper.

A most important object of my invention is to provide a hair-clipping attachment device, having an automatically adjustable gauge which is actuated through a finger engaged by the moving arm of the hair clipper, linked to a pawl and ratchet means to cause the rotation of a central screw, which, through a second linkage means, controls the angle of the hinged automatically adjustable gauge, tilting the said gauge to provide a progressively increasing angle between the said automatically adjustable gauge and the hair clipper guide plate.

A still further object of my invention is to provide an escapement device actuated by the central screw, whereby, at regular intervals, the said escapement device will cause the readjustment of the automatically adjustable gauge as the clippers are operated, thus providing a limit control to the angle between the said adjustable gauge and the clipper.

A still further object of my invention is to provide, in a hair-clipping attachment device, an adjustable locking means whereby the hair-clipping attachment device may be rendered inoperative, if desired.

A still further object of my invention is to provide adjustment means for varying the magnitude of angular movement with each stroke of the moving arm of the hair clipper.

A still further object of my invention is to provide a quick and easy means of adjusting the angle between the automatically adjustable gauge of the said hair-clipping attachment device and the hair clipper at the start of each cutting operation.

A still further object of my invention is to provide a hair-clipping attachment device that may be mass produced as a unit and that may be attached quickly and easily to any standard hair clipper.

Other objects and advantages inherent in my invention will be disclosed by the following description and the accompanying illustrations, in which like parts are designated by like numerals, and in which:

Fig. 1 is a perspective view of my invention shown attached to a hair clipper with parts cut away to disclose its working mechanism.

2.

Fig. 2 is a top or plan view of my invention.

Fig. 3 is a cross-sectional view of my invention taken substantially on line 3—3 of Fig. 2.

Fig. 4 is a rear view of my invention taken looking in the direction of lines 4—4 of Fig. 3.

Fig. 4a is a fragmentary view of my invention, looking in the direction of line 4a—4a on Fig. 3, showing the operative position of the adjustable locking means.

Fig. 5 is a view of a portion of my invention, partly in cross section, looking in the direction of line 5—5 of Fig. 4.

Fig. 6 is a bottom view of my invention looking in the direction of line 6—6 of Fig. 3.

Fig. 7 is a perspective view of the linkage means comprising a part of my invention.

Fig. 8 is a cross-sectional view of a portion of my invention taken substantially on the lines 8—8 of Fig. 2.

20 My invention is generally designated 9 and consists of a lower frame 10, which is attached to the hair-clipper guide 11 by screws 12 on the bottom of the hair clipper. Hinged to a pair of ears 13, located one on either side of the frame 10, are the arms 14 of the automatically adjustable gauge 15 which is held in position slightly below the said frame 10. A toothed extension 16 is adjustably attached to the adjustable gauge 15, by means of screws 17 and slots 18 in the said adjustable gauge, and its rear portion is tapered and cambered to provide a thumb adjustment means 19.

Mounted upon frame 10 is a block 21 in a central hole 15 of which is supported the reduced end of an arbor 22 maintained therein by a reduced threaded portion 24 extending through an opening in the frame 10 and secured thereto by lock nuts 23.

40 A flat 25 on the arbor 22 provides attaching means for a ratchet wheel 26 which is spaced by a washer 27 from block 21. A second washer 28 on the arbor 22 separates the ratchet wheel 26 from a bracket 35 which rotates freely thereon. Upon the upper threaded portion 30 of the arbor 22, a second ratchet wheel 29 is secured and held 45 in place by a shoulder lock nut 31. An ovoid-shaped washer 33 is mounted rotatably between the shoulder lock nut 31 and the ratchet wheel 29, and is attached to the bracket 35 by a pivot pin 34, which serves as a pivoting means for a pawl 32. The tooth of the pawl 32 being maintained in contact with the teeth of the ratchet wheel 29 by spring 36 mounted on bracket 35.

One end of a coil spring 36 is attached to the bracket 35; the other end being held by a pin 37, mounted on the block 21. The said spring 36 is

maintained in position around the circumference of the ratchet wheel 29 by a semi-circular guard 38 attached to the bracket 35, as shown in Fig. 5. A bent arm 41 is pivotally attached at 44 to one of two upright posts 43 fixedly set in the block 21. A linkage means 39 articulately connects the angular bracket 40 on arm 41 to an ear on the bracket 35. An engaging finger 42 is vertically mounted upon the straight portion of the bent arm 41.

Slidably mounted upon the upright posts 43 by means of sleeves 46 is an escapement assembly frame 47. Two gripping members 50 are pivoted at 48 and held in place by a plate 49 on the top of the frame 41. The gripping members 50 are provided with enlarged mating portions 53, which are threaded at 54 to form a split nut engaging releasably the threaded portion 39 of the rotating arbor 22. A coil spring 51 is mounted between two ears 52 on the handle ends of the two gripping members 50, the said ears 52 also serving as thumb and finger adjusting means for tripping the escapement means provided by the split nut 53 and the screw 39. A U-shaped strap 56 forms a guide slot with the top of the escapement frame 47 providing a guide and holding means for the tips 55 of the gripping members 50. A knurled cap 57 may be provided for the top of the threaded portion 39 of the arbor 22 when a quick rotary adjustment thereof is desired.

A link 60 is articulately mounted between a pair of spacers 58 mounted upon the extending ends of the frame 47 and held by a pin 59 therethrough. The link 60 passes through a slot 61 in the frame 10 and is articulately attached by pins 62 to the automatically adjustable gauge 15. Two coil springs 19 are attached between the arms 14 on the said adjustable gauge 15 and angles 20 attached to the frame 10.

A locking and adjustment means for the hair clipper attachment device is provided and consists of a slot 63 formed in the rear extension 81 of the frame 10. An angle 64 is slidably maintained on said extension 81 by shoulder screw 65, a key 82, and a knurled lock nut 66 extends through the slot 63. Pivotably mounted upon the angle 64 and frictionally maintained, in either an upright operative, or a down and inoperative position, is an engaging arm 67, having attached thereto a manipulating finger 68.

To operate the hair clipping device, the automatically adjustable gauge 15 is set to the desired angle by gripping the ears 52 with the thumb and finger to release the escapement mechanism and allow the said adjustable gauge 15 to be manipulated by the thumb adjustment means 69. As illustrated by phantom lines in Fig. 3, this preliminary adjustment is usually to place the toothed extension 16 attached to the automatically adjustable gauge 15 in as close as possible a relationship to the hair clipper guide 11 at the start of the cutting operation. The toothed extension 16 is placed against the scalp 70 allowing the hair 71 to extend upwardly between the teeth 74, as shown in Fig. 3.

The movable arm 45 of the clipper 10 is manipulated, in the directions of arrow 73 in Fig. 2, causing the hair to be clipped or shorn by the toothed reciprocator blade 72, the said arm 45 being in engagement with the engaging finger 42 of the hair clipping device. Since the engaging finger 42 is connected through the arm 41 and the linkage 39 to the pawl actuating bracket 35, therefore each stroke or movement of the moving member 45 will cause a partial rotation of the

ratchet wheel 29 and the arbor 22 to which it is secured, the threaded portion 30 of the said arbor 22 being engaged by the split nut 53 of the escapement mechanism. Therefore, each turn of the arbor 22 will cause an upward movement of the escapement device 47 and, through linkage 60, to the automatically adjustable gauge 15, increasing the angle between the toothed extension 16 attached thereto and the hair clipping guide 11 with each movement of the clipper arm 45. The progressive widening of the angle 78 between the automatically adjustable gauge 15 and the hair clipper guide 11 will provide a tapered cut to the hair, as illustrated in Fig. 3 in phantom and solid lines.

After the tapering has been finished, the angle 78 between the automatically adjustable gauge 15 and the hair clipper guide 11 will have reached its widest extension and, since it is desirable to maintain an even cut thereafter, an escapement mechanism has been provided to allow this. The escapement mechanism is best illustrated in Figs. 2, 3, and 8. Dotted lines in Figs. 2 and 8 show the threads 54 of the split nut 53 in engagement with the threaded portion 30 of the arbor 22. As the arbor 22 is rotated in the manner heretofore described, the escapement mechanism will be raised, thread by thread, until the tension from the springs 19, which are counteractive to the downward pressure of the link 60, becomes greater than the holding means of the coiled spring 51 which, through the gripping members 50, maintains the split nut 53 in threadable contact with the screw 30. When this happens, the threads 54 of the split nut 53 will be forced out of contact with the threaded portion 30 of the arbor 22, as shown in solid lines in Fig. 8.

The tension of the said spring 19 will cause the escape mechanism to drop a distance of one thread on the threaded portion 30 of the said arbor 22, thereupon the threads 54 of the split nut 53 will again be urged into contact with the threaded portion 30 by spring 51, thus slightly adjusting the angle 78 between the automatically adjustable gauge 15 and the hair clipper guide 11. The ratchet wheel 26, together with the spring-urged pawl 27, which is pivoted at 28 on block 20, prevents backlash of the arbor 22 on which the said ratchet wheel 26 is mounted. This automatic adjustment will be repeated as long as the clipping operation lasts, and is comparable to the manual adjustment made by barbers as they manipulate the barber clippers in cutting hair.

With this hair clipping device both the taper and the even cut of the hair is automatically maintained by the action of the hair clipping device through its automatically adjustable gauge, together with the escapement mechanism, so that an average person may operate the hair clipping device and obtain results to compare favorably with those of a professional barber.

If it is desirable to operate the hair clipper without making use of the automatic features of the adjustable hair clipping device, the said device may be locked to an inoperative position by means of an adjusting and locking assembly, best illustrated in Figs. 4 and 4a, in which the sliding angular bracket 64 is shown locked in two positions. In the position shown in solid lines, the arm 67 is depressed allowing the actuating arm 41, through its link 39, to provide a maximum arc of rotation to the rotating bracket 35 as the movable clipper arm 45 is manipulated. In the phantom lines, the arm 67 is shown in a raised posi-

tion and the sliding angular bracket 64 is shown in an adjusted position locked by the knurled nut 66. In this position the arc of rotation of the rotating bracket 35 is limited to a shorter or more restricted arc reducing the rate of angular adjustment of the automatically adjustable gauge 15.

Fig. 4a shows the angle 64 set at its outermost point, as in solid lines in Fig. 4, but with the arm 67 raised to an operative position and with the actuating arm 41 maintained and locked at the innermost position of its articulate movement, so that the engaging finger 42 will not be engaged by the moving arm 45 of the clipper. The automatically adjustable gauge 15, however, may still be adjusted to any desirable angle within its range to provide an even cut of hair at that adjustment. The rear edge of the extension 81 may be notched or marked as at 79 and 80 for purposes of aligning the sliding angular bracket 64 to its two adjusting and locking positions within the slot 63. The adjusting is easily performed by loosening the knurled cap 66, sliding the angular bracket 64 to its desirable position and retightening the said cap 66.

Since this hair clipping device, by means of its automatically adjustable gauge and its escapement device, automatically provides all of the adjustments and guides necessary in cutting hair; therefore, it should be of the greatest value to non-professional users in enabling them to achieve professional-appearing hair cuts.

Although I have thus described my invention with great particularity, it will be clear to those persons familiar with the art that the same may be modified throughout a wide range. I, accordingly, do not propose to be limited to the exact details of construction herein shown and described, but reserve in practice to make any modifications which may come within the spirit and scope of the subjoined claims.

Having thus disclosed and revealed my invention, what I claim as new and desire to secure by Letters Patent is:

1. Automatically adjustable hair clipper attachment means comprising, a frame removably securable to a hair clipper, a block support mounted rearwardly on the said frame, an arbor rotatably mounted in the said block support and having a threaded extension, ratchet means secured to the said arbor, motivating pawl and check pawl means cooperating with the said ratchet means, linkage means connected to the said motivating pawl and check pawl means, the said linkage means provided with finger means engageable by the moving arm of a hair clipper to which the said clipper attachment means may be secured, escapement means provided with split nut means engaging the threaded extension of the said arbor, adjustable hair gauging means pivotably attached to the said frame, and link means interconnecting the said escapement means to the said adjustable hair gauging means.

2. Automatically adjustable hair clipper attachment means comprising, a frame removably securable to a hair clipper, a block support mounted rearwardly on the said frame, an arbor rotatably mounted in the said block support and having a threaded extension, ratchet means secured to the said arbor, motivating pawl and check pawl means cooperating with the said ratchet means, linkage means connected to the said motivating pawl and check pawl means, the said linkage means provided with finger means engageable by the moving arm of a hair clipper to which the said clipper

attachment means may be secured, escapement means provided with split nut means engaging the threaded extension of the said arbor, adjustable hair gauging means pivotably attached to the said frame, link means interconnecting the said escapement means to the said adjustable hair gauging means, the said split nut means provided with gripping arm extensions, and spring means maintaining normally the said split nut means in engagement with the threaded extension of the said arbor.

3. Automatically adjustable hair clipper attachment means comprising, a frame removably securable to a hair clipper, a block support mounted rearwardly on the said frame, an arbor rotatably mounted in the said block support and having a threaded extension, ratchet means secured to the said arbor, motivating pawl and check pawl means cooperating with the said ratchet means, linkage means connected to the said motivating pawl and check pawl means, the said linkage means provided with finger means engageable by the moving arm of a hair clipper to which the said clipper attachment means may be secured, escapement means provided with split nut means engaging the threaded extension of the said arbor, adjustable hair gauging means pivotably attached to the said frame, link means interconnecting the said escapement means to the said adjustable hair gauging means, and spring means connecting the said adjustable hair gauging means to anchorage means on the said frame to limit the adjustment of the said adjustable hair gauging means.

3.5. 4. Automatically adjustable hair clipper attachment means comprising, a frame removably securable to a hair clipper, a block support mounted rearwardly on the said frame, an arbor rotatably mounted in the said block support and having a threaded extension, ratchet means secured to the said arbor, motivating pawl and check pawl means cooperating with the said ratchet means, linkage means connected to the said motivating pawl and check pawl means, the said linkage means provided with finger means engageable by the moving arm of a hair clipper to which the said clipper attachment means may be secured, escapement means provided with split nut means engaging the threaded extension of the said arbor, adjustable hair gauging means pivotably attached to the said frame, link means interconnecting the said escapement means to the said adjustable hair gauging means, the said split nut means provided with gripping arm extensions, spring means maintaining normally the said split nut means in engagement with the threaded extension of the said arbor, and spring means connecting the said adjustable hair gauging means to anchorage means on the said frame to limit the adjustment of the said adjustable hair gauging means.

5. Automatically adjustable hair clipper attachment means comprising, a frame removably securable to a hair clipper, a block support mounted rearwardly on the said frame, an arbor rotatably mounted in the said block support and having a threaded extension, ratchet means secured to the said arbor, motivating pawl and check pawl means cooperating with the said ratchet means, linkage means connected to the said motivating pawl and check pawl means, the said linkage means provided with finger means engageable by the moving arm of a hair clipper to which the said clipper attachment means may be secured, escapement means provided with split

nut means engaging the threaded extension of the said arbor, adjustable hair gauging means pivotably attached to the said frame and link means interconnecting the said escapement means to the said adjustable hair gauging means, and adjusting and locking means secured to the said frame and adapted to adjust the movement of the said motivating pawl and check pawl means.

6. Automatically adjustable hair clipper attachment means comprising, a frame removably securable to a hair clipper, a block support mounted rearwardly on the said frame, an arbor rotatably mounted in the said block support and having a threaded extension, ratchet means secured to the said arbor, motivating pawl and check pawl means cooperating with the said ratchet means, linkage means connected to the said motivating pawl and check pawl means, the said linkage means provided with finger means engageable by the moving arm of a hair clipper to which the said clipper attachment means may be secured, escapement means provided with split nut means engaging the threaded extension of the said arbor, adjustable hair gauging means pivotably attached to the said frame and link means interconnecting the said escapement means to the said adjustable hair gauging means, the said split nut means provided with gripping arm extensions, spring means maintaining normally the said split nut means in engagement with the threaded extension of the said arbor, and adjusting and locking means secured to the said frame and adapted to adjust the movement of the said motivating pawl and check pawl means.

7. Automatically adjustable hair clipper attachment means comprising, a frame removably securable to a hair clipper, a block support mounted rearwardly on the said frame, an arbor rotatably mounted in the said block support and having a threaded extension, ratchet means secured to the said arbor, motivating pawl and check pawl means cooperating with the said ratchet means, linkage means connected to the said motivating pawl and check pawl means, the said linkage means provided with finger means engageable by the moving arm of a hair clipper to which the said clipper attachment means may be secured, escapement means provided with split nut means engaging the threaded extension of the said arbor, adjustable hair gauging means pivotably attached to the said frame and link means interconnecting the said escapement means to the said adjustable hair gauging means, spring means connecting the said adjustable hair gauging means to anchorage means on the said frame to limit the adjustment of the said adjustable hair gauging means, and adjusting and locking means secured to the said frame and adapted to adjust the movement of the said motivating pawl and check pawl means.

8. Automatically adjustable hair clipper attachment means comprising, a frame removably securable to a hair clipper, a block support mounted rearwardly on the said frame, an arbor rotatably mounted in the said block support and having a threaded extension, ratchet means secured to the said arbor, motivating pawl and check pawl means cooperating with the said ratchet means, linkage means connected to the said motivating pawl and check pawl means, the said linkage means provided with finger means engageable by the moving arm of a hair clipper to which the said clipper attachment means may be secured, escapement means provided with split

nut means engaging the threaded extension of the said arbor, adjustable hair gauging means pivotably attached to the said frame and link means interconnecting the said escapement means to the said adjustable hair gauging means, the said split nut means provided with gripping arm extensions, spring means maintaining normally the said split nut means in engagement with the threaded extension of the said arbor, and adjusting and locking means secured to the said frame and adapted to adjust the movement of the said motivating pawl and check pawl means.

9. Automatically adjustable hair clipper attachment means comprising, a frame removably securable to a hair clipper, a block support mounted rearwardly on the said frame, an arbor rotatably mounted in the said block support and having a threaded extension, ratchet means secured to the said arbor, motivating pawl and check pawl means cooperating with the said ratchet means, linkage means connected to the said motivating pawl and check pawl means, the said linkage means provided with finger means engageable by the moving arm of a hair clipper
15 20 to which the said clipper attachment means may be secured, escapement means provided with split nut means engaging the threaded extension of the said arbor, adjustable hair gauging means pivotably attached to the said frame, link means
25 30 interconnecting the said escapement means to the said adjustable hair gauging means, and adjusting and locking means secured to the said frame and adapted to adjust the movement of the said motivating pawl and check pawl means,
35 and further adapted to lock the said motivating pawl and check pawl means in inoperative position.

10. Automatically adjustable hair clipper attachment means comprising, a frame removably securable to a hair clipper, a block support mounted rearwardly on the said frame, an arbor rotatably mounted in the said block support and having a threaded extension, ratchet means secured to the said arbor, motivating pawl and check pawl means cooperating with the said ratchet means, linkage means connected to the said motivating pawl and check pawl means, the said linkage means provided with finger means engageable by the moving arm of a hair clipper to 45 which the said clipper attachment means may be secured, escapement means provided with split nut means engaging the threaded extension of the said arbor, adjustable hair gauging means pivotably attached to the said frame, link means interconnecting the said escapement means to the said 50 adjustable hair gauging means, the said split nut means provided with gripping arm extensions, spring means maintaining normally the said split nut means in engagement with the threaded extension of the said arbor, and adjusting and locking means secured to the said frame and adapted to adjust the movement of the said motivating pawl and check pawl means, and further adapted to lock the said motivating pawl and check pawl 55 means in inoperative position.

11. Automatically adjustable hair clipper attachment means comprising, a frame removably securable to a hair clipper, a block support mounted rearwardly on the said frame, an arbor 70 rotatably mounted in the said block support and having a threaded extension, ratchet means secured to the said arbor, motivating pawl and check pawl means cooperating with the said ratchet means, linkage means connected to the 75 said motivating pawl and check pawl means, the

said linkage means provided with finger means engageable by the moving arm of a hair clipper to which the said clipper attachment means may be secured, escapement means provided with split nut means engaging the threaded extension of the said arbor, adjustable hair gauging means pivotally attached to the said frame, link means interconnecting the said escapement means to the said adjustable hair gauging means, spring means connecting the said adjustable hair gauging means to anchorage means on the said frame to limit the adjustment of the said adjustable hair gauging means, and adjusting and locking means secured to the said frame and adapted to adjust the movement of the said motivating pawl and check pawl means, and further adapted to lock the said motivating pawl and check pawl means in inoperative position.

12. Automatically adjustable hair clipper attachment means comprising, a frame removably securable to a hair clipper, a block support mounted rearwardly on the said frame, an arbor rotatably mounted in the said block support and having a threaded extension, ratchet means secured to the said arbor, motivating pawl and check pawl means cooperating with the said ratchet means, linkage means connected to the said motivating pawl and check pawl means, the said linkage means provided with finger means engageable by the moving arm of a hair clipper to which the said clipper attachment means may

be secured, escapement means provided with split nut means engaging the threaded extension of the said arbor, adjustable hair gauging means pivotably attached to the said frame, link means interconnecting the said escapement means to the said adjustable hair gauging means, the said split nut means provided with gripping arm extensions, spring means maintaining normally the said split nut means in engagement with the threaded extension of the said arbor, spring means connecting the said adjustable hair gauging means to anchorage means on the said frame to limit the adjustment of the said adjustable hair gauging means, and adjusting and locking means secured to the said frame and adapted to adjust the movement of the said motivating pawl and check pawl means, and further adapted to lock the said motivating pawl and check pawl means in inoperative position.
